[57] CLAIM

The ornamental design for a device for converting a downhill ski binding to a cross-country ski binding, substantially as shown and described.

DESCRIPTION

FIG. 1 is a side perspective view of a device for converting a downhill ski binding to a cross-country ski binding showing my new design, the side opposite being substantially a mirror image;

FIG. 2 is a top perspective view thereof; and
FIG. 3 is a front perspective view thereof.

FIG. 3

FIG. 1

FIG. 2
